UNITED STATES PATENT OFFICE.

JAMES K. RICHIE, OF BUTLER, PENNSYLVANIA.

ILLUMINATOR FOR LAMPS AND SWITCHES.

1,367,891.

Specification of Letters Patent.

Patented Feb. 8, 1921.

Application filed April 9, 1919. Serial No. 288,773.

To all whom it may concern:

Be it known that I, JAMES K. RICHIE, a citizen of the United States, residing at Butler, in the county of Butler and State 5 of Pennsylvania, have invented a new and useful Illuminator for Lamps and Switches, of which the following is a specification.

It is the object of this invention to provide a simple means whereby an article, 10 such as a luminous element, may be held upon a lamp socket, on a switch, or on a like member, for the purpose of illuminating a switch button, the finger piece of the lamp socket, the rotary member of a switch, or 15 the like, the device being equally applicable for use in connection with door bells, medicine bottles, match boxes or the like, to hold in close relation to devices of the kind mentioned, either a luminous member, or a 20 marker of any desired sort.

It is within the province of the disclosure to improve generally and to enhance the utility of devices of that type to which the invention appertains.

25 With the above and other objects in view, which will appear as the description proceeds, the invention resides in the arrangement and combination of parts and in the details of construction hereinafter described 30 and claimed, it being understood that, within the scope of what is claimed, changes in the precise embodiment of the invention shown can be made without departing from the spirit of the invention.

35 In the drawings:-

Figure 1 shows in elevation, a lamp socket whereunto the device forming the subject matter of this application has been applied, parts appearing in section; Fig. 2 is a fragmental elevation showing the structure assembled with a push button; Fig. 3 is a perspective showing the device detached, parts being omitted; and Fig. 4 is an elevation showing a rotary switch to which 45 the structure claimed has been applied, parts appearing in section.

The device hereinafter claimed may be made of any desired material, bendable metal being preferred. The structure includes a body 1 having a projecting end flange 2 and side flanges 3, the flanges 2 and 3 being supplied with projections or teeth 4, which are bendable. The plate, a portion 50 of which forms the body 1, is crimped upon itself, transversely, to form a rib 5 of inverted U-shape, disposed at the inner ends

of the side flanges 3. The structure terminates in a bendable end 6 having an opening 7.

The flanges 2 and 3 and the rib 5 define 60 a socket, into which an article of any desired sort may be inserted. Although I do not bind myself as to the particular construction of the article above alluded to, the article may comprise a layer of luminous material 65 indicated at 8, on which a transparent shield 9 is superposed, the shield, ordinarily, being made of glass. Obviously, without effecting a change in the showing of the drawings, a numbered sheet may replace the luminous 70 material 8 if the device is to be used on a medicine bottle, a match box or the like, and the inscription on the sheet may be of any desired sort.

When the article, whatever be its construction, has been mounted in the socket above defined, the projections or teeth 4 are bent over parallel to the body 1 to hold the article in place.

The applications of the device are many, 80 but, as illustrating one use to which the structure may be put, a screw 10 or like securing element may be passed through the opening 7, to hold the structure on the base 100 of a switch, including a push button 12, 85 the luminous material serving to light up the push button so that the same can be found readily in the dark.

This application of the invention is disclosed in Fig. 2.

90 Passing to Fig. 4, it will be noted that the end 6 may be bent at right angles to the body 1 and be inserted between the shell 15 and the insulation 16 of a switch 17 including a finger piece 25, the function of the luminous 95 material 8 being to render the finger piece 25 visible.

Passing to Fig. 1, the bendable end 6 may remain in alignment with the body 1 as shown at 18, and be inserted between the 100 parts 19 and 20 of a lamp socket 21, and may be disposed as close as desired to the finger piece 22 of the lamp socket.

From the foregoing it will be clear that a means is provided whereby an article of 105 any kind, such as a luminous member, an index or the like may be held in place on a structure of any sort wherewith the article is adapted to be used.

A rib 5 serves to strengthen the device 110 and forms, as well, one part of the socket hereinbefore alluded to. Further, when

the end 6 is disposed at right angles to the body 1, as indicated at 14 in Fig. 4, the end coöperates and bears against the rib, the strength of the structure being enhanced.

5 Having thus described the invention, what is claimed is:—

A device of the class described comprising a strip bent transversely to form a rib of inverted U-shape, the rib being extended 10 entirely across the strip, the rib defining a body and an end of the same width as the body, the body and the end being located in the same plane, the rib comprising inner and outer walls, both of which project be- 15 yond said plane, the end having an opening, the body being supplied with marginal teeth disposed in groups and coöperating with the

inner wall of the rib to form a socket, the end being bendable at right angles to the body along the line of juncture between the 20 end and the outer wall of the rib into abutment with the outer wall of the rib, the rib being of sufficient height so that the outer wall of the rib will form an efficient abutment for the end when the end is bent; and 25 an article in the socket, the teeth being bendable to overhang the article.

In testimony that I claim the foregoing as my own, I have hereto affixed my signature in the presence of two witnesses.

JAMES K. RICHIE.
